UNITED STATES PATENT OFFICE.

HENRY HAYDOCK AND DANIEL PARKES, OF BLACKBURN, ENGLAND.

SHUTTLE FOR LOOMS FOR WEAVING.

1,100,561.

Specification of Letters Patent. Patented June 16, 1914.

Application filed February 6, 1912. Serial No. 675,805.

To all whom it may concern:

Be it known that we, HENRY HAYDOCK and DANIEL PARKES, British subjects, residing both at Blackburn, county of Lancashire, England, have invented certain new and useful Improvements in Shuttles for Looms for Weaving, of which the following is a specification.

This invention relates to loom shuttles in which the threading is effected by passing the thread through a slit in the top of the shuttle around a block which threads it into or presents it to the eye or orifice in the side of the shuttle from which it is withdrawn by the fingers of the operative to obviate the common practice of drawing the thread through the eye by suction of the mouth.

The invention consists essentially in constructing the shuttle with a curved slit or inclined slits in the top leading down to internal thread passages and direct to the closed shuttle eye thereby forming a block in the fore part of the shuttle preferably integral therewith by which the yarn is directed to the eye in the side of the shuttle.

The invention will be fully described with reference to the accompanying drawings forming part of the specification.

Figure 1. is a side elevation of the fore part of shuttle. Fig. 2. is a plan. Fig. 3. is a longitudinal sectional elevation. Fig. 4. is a sectional plan. Fig. 5. is a transverse section on line $x-x$ of Fig. 3. Fig. 6 is a transverse section on line $y-y$ of Fig. 3.

In the fore part of the shuttle an internal yarn passage A is formed extending from the center of the shuttle longitudinally and opening laterally at a into the eye B in the side of the shuttle. A slit C of curved form is cut from the top of the shuttle into the passage A through which the yarn is passed downward into the passage A at one side and the eye B at the other side. The slit C is preferably curved though it may be in the form of two slits set at an inclination to one another and joining at the apex. The slit or slits thus cut leave or form a block D in front of the shuttle peg G around which the yarn can be passed to thread the shuttle. The block D is curved or circular when the slit is curved but where two in-

clined slits are cut the block D would be triangular.

A steel pin c is set across or in front of the yarn slit C above the yarn passage A to prevent the yarn rising or ballooning in the slit C. And a wire or pin E is fitted vertically or approximately vertically in front of the yarn passage A to guide the yarn thereto. In operation the end of the pin c overlaps the wire E and the two in conjunction prevent any escape of the yarn when the shuttle is in operation.

The yarn passage may be directly opposite the end of the shuttle peg G or to one side thereof. Steel pins b b' may be inserted at either side of the shuttle eye B to prevent wear. A pin e may be inserted at the junction of the yarn passages A and a to prevent the yarn cutting or wearing into the block.

The hole a' is bored for the convenience of construction and to prevent the possibility of the yarn being drawn through the passage A by suction through the eye B. The yarn from the shuttle peg G is drawn out and passed around the block D and into the yarn passage A at one side and drawn out through the eye B at the other side by the fingers of the operative.

No fittings or attachment to the shuttle are required as the block D is homogeneous therewith being cut out of the solid wood of the shuttle thereby preserving its balance.

What we claim as our invention and desire to protect by Letters Patent is:—

1. A loom shuttle constructed with a longitudinal internal yarn passage, a transverse internal yarn passage communicating with the longitudinal passage and terminating in a closed yarn eye and a yarn slit cut into the top of the shuttle and extending downward into the yarn passages and into the shuttle eye and forming a block integral with the shuttle around which the yarn is threaded substantially as described.

2. A loom shuttle constructed with a longitudinal internal yarn passage, a transverse internal yarn passage communicating with the longitudinal passage and terminating in a closed yarn eye, a yarn slit cut into the top of the shuttle and extending downward

into the yarn passage and into the shuttle eye and forming a block integral with the shuttle around which the yarn is threaded, a pin projecting across the slit above the 5 yarn passage to prevent the yarn from rising through said slit and a second pin arranged vertically in front of said yarn passage to guide the yarn thereto.

In testimony whereof we have hereunto set our hands in presence of two subscribing 10 witnesses.

HENRY HAYDOCK.
DANIEL PARKES.
